US00D976504S

(12) United States Design Patent (10) Patent No.: US D976,504 S
(45) Date of Patent: * Jan. 24, 2023

(54) MASSAGE DEVICE FOR ANIMALS

(71) Applicant: Rimene OÜ, Saue vald (EE)

(72) Inventors: Mait Boisen, Saue vald (EE); Piia Susi, Saue vald (EE)

() Term: 15 Years

(21) Appl. No.: 35/511,922

(22) Filed: May 12, 2021

(80) Hague Agreement Data

Int. Filing Date: May 12, 2021

Int. Reg. No.: DM/214278

Int. Reg. Date: May 12, 2021

Int. Reg. Pub. Date: May 28, 2021

(51) LOC (14) Cl. 30-99

(52) U.S. Cl.

USPC D30/199; D24/215

(58) Field of Classification Search

USPC D30/158, 160, 199; D24/128, 200, 214, D24/215, 233; D4/127; D8/107, 373; D28/11, 35, 38

CPC A01K 13/002
